UNITED STATES PATENT OFFICE.

DANIEL W. BARTON, OF OSHKOSH, WISCONSIN, ASSIGNOR TO WARREN G. MAXCY, OF OSHKOSH, WISCONSIN.

MEANS FOR INSULATING ELECTROMAGNETS.

1,174,958.

Specification of Letters Patent.

Patented Mar. 14, 1916.

Application filed May 16, 1913. Serial No. 767,981.

To all whom it may concern:

Be it known that I, DANIEL W. BARTON, a citizen of the United States, and resident of Oshkosh, in the county of Winnebago and

5 State of Wisconsin, have invented new and useful Improvements in Means for Insulating Electromagnets, of which the following is a description, reference being had to the accompanying drawings, which are a part

10 of this specification.

This invention relates to improvements in means for insulating electromagnets from their supports and more particularly to magnets for playing musical instruments.

15 In constructing electromagnets for use in playing musical instruments in which one vibrating magnet is used for each note of the instrument played it has been found difficult to independently insulate each mag-

20 net and also to prevent the vibration of the magnet armatures from being transmitted to the instrument support and thereby blast or interfere with the clear vibratory sounds of the notes played.

25 It is one of the objects of the present invention to overcome the objectionable features mentioned and provide a means for insulating electromagnets from their supports which is adapted to insulate the magnets

30 from each other and from their supports both electrically and vibratorily.

A further object of the invention is to provide a means for insulating electromagnets from their supports which is of simple

35 construction, is easily assembled, is strong and durable and is well adapted for the purpose described.

With the above and other objects in view, the invention consists of the improved

40 means for insulating electromagnets from their supports and its parts and combinations as set forth in the claims, and all equivalents thereof.

In the accompanying drawing in which

45 the same reference characters indicate the same parts in all of the views: Figure 1 is a top view of one end portion of a support with two electromagnets mounted thereon; Fig. 2 is a transverse sectional view thereof;

50 Fig. 3 is a longitudinal sectional view on a larger scale of one portion of the supporting rod; and Fig. 4 is a fragmentary detail side view of the support.

Referring to the drawing the numeral 8

indicates one end portion of the supporting 55 frame which is provided with transverse recesses or slots 9 to receive the end portions of metal supporting rods 10 extending therethrough. The transverse recesses are provided with half bushings 11 of felt or other 60 yielding material upon which the rods rest. The rods are also provided with yielding washers 12 of similar material positioned on opposite sides of the frame which are held in place by metal washers 13 and by 65 nuts 14 threaded on the rods. While the rods are only shown as supported on one end it is to be understood that both ends are to be supported and insulated in a similar manner. 70

The electromagnets used on the supporting frames are of usual construction the leading in wire being connected up to one of the coils and the return wire being connected to the frame, the second coil being grounded 75 on the frame. Thus the current passes through the coils and frame so that it is necessary to insulate the frames of the different magnets from each other. This is accomplished by insulating the frames from 80 the supporting rods upon which they are mounted in a manner hereinafter described.

The medial portions of the rods are covered with sleeves 15 preferably of wood or other insulating material which serve to insulate the metal frames 16 of the electromagnets 17 from the rods and also serve to absorb or insulate the vibrations of the magnets from the rods 10 and the supporting frame 8. The opposite ends of the sleeves 85 are reduced in diameter to form shoulders 18 which abut against the sides of the magnet frames and also form reduced end portions 19 which extend into the bores 20 of the magnet frames. The reduced end portions 90 10 are slightly less in length than half of the thickness of the magnet frames to provide for the shoulders tightly clamping the frames therebetween. The sleeves are held in proper position on the rods by nuts 21 100 threaded on the opposite end portions of the rods and yielding and metal washers 22 and 23 respectively, which are interposed between the nuts and the end sleeves.

From the foregoing description it will be 105 seen that the vibrations of the magnet are insulated from the supporting frame which is also adapted to support the musical in-

strument played and the magnet frames are also electrically insulated from each other and from the supporting frame.

What I claim as my invention is:

- 5 1. The combination with an electromagnetic instrument player, of an electrical and vibratory insulating means therefor, comprising a rod extending through the magnet frame, an insulator sleeve surrounding the 10 rod and interposed between the frame and the rod, and a support for the rod.
- 15 2. The combination with an electromagnetic instrument player, of an electrical and vibratory insulating means therefor, comprising a support, a rod extending through the support, a yielding connection interposed between the rod and the support, a frame forming part of the electromagnet mounted on the rod, and an insulating sleeve 20 having a reduced end portion which enters a part of the frame and also having a shouldered portion which abuts against a side portion of the frame.
- 25 3. The combination with an electromagnetic instrument player, of an electrical and vibratory insulating means therefor, comprising a support having an opening extending therethrough, a rod extending through the opening, a yielding material positioned 30 within the opening and interposed between the rod and the support, a yielding washer surrounding the rod and positioned alongside of the support, a frame forming part of the electromagnet mounted on the rod, and an insulating sleeve 35 having a reduced end portion which enters a part of the frame and also having a shouldered portion which abuts against a side portion of the frame.
- 40 4. The combination with an electromagnetic instrument player, of an electrical and

vibratory insulating means therefor, comprising a support, a metal rod carried by the support, a plurality of spaced electromagnet frames having openings through which the rod passes, and insulating sleeves surrounding the rod and interposed between the magnet frames to space said frames apart and to insulate them from each other and the rod. 45

5. The combination with an electromagnetic instrument player, of an electrical and vibratory insulating means therefor, comprising a support, a metal rod carried by the support, a plurality of spaced electromagnet frames having openings through which the rod passes, and insulating sleeves surrounding the rod and interposed between the magnet frames to space said frames apart and to insulate them from each other and the rod, 50 said sleeves having reduced end portions which enter the magnet frames and also 55 having shouldered portions which abut against the magnet frames.

6. The combination, with a plurality of electromagnets of an electrical player, of rods passing through the frames of the magnets and means for insulating the frames from each other against vibration consisting of non-vibratory sleeves surrounding the rods and interposed between the rods and the frames, a support for the rods having 65 slots therein and non-vibratory yielding material disposed in said slots between the support and the rods. 70

In testimony whereof, I affix my signature, in presence of two witnesses.

DANIEL W. BARTON.
